UNITED STATES PATENT OFFICE.

CHARLES EDWARD ASHBURNER, OF LYNCHBURG, VIRGINIA.

TOY PUZZLE.

1,072,558.

Specification of Letters Patent.

Patented Sept. 9, 1913.

Application filed April 12, 1913. Serial No. 760,779.

To all whom it may concern:

Be it known that I, CHARLES E. ASHBURNER, a citizen of the United States, and a resident of Lynchburg, in the county of

5 Campbell and State of Virginia, have invented certain new and useful Improvements in Toy Puzzles, of which the following is a full and clear specification, reference being had to the accompanying drawings, in which—

10 Figure 1 is a plan view of a preferred form of my device; Fig. 2 a sectional view on the line 2—2 of Fig. 1; Fig. 3 a sectional view on the line 3—3 of Fig. 1; and Fig. 4 15 a fragmentary bottom view of a portion of the partitions removed from the casing or box.

The device consists essentially of a casing having a flat bottom *a*, an upright marginal 20 wall *b* and a cover *c* of glass or other transparent material. The glass cover *c* may be omitted without departing from my invention, and while I have illustrated a rectangular casing or box it will be understood 25 that other shapes may be employed.

The interior of the box is divided into a multiplicity of pockets or chambers *d* by intersecting partitions extending entirely across the box. In the form of my device 30 illustrated I have shown these partitions as being arranged at right angles to each other and to the side walls of the box to thereby give a rectangular form to the compartments *d*, but I desire it understood that the partitions may be arranged otherwise and that the compartments may be shaped otherwise 35 or increased or decreased in number without departing from the spirit of my invention. Resting on the bottom *a* of the box and

40 adapted to freely roll thereon is a ball *b*. The lower edges of the partitions are provided with a series of notches *f*, *f'*, these notches serving to put the adjacent chambers into communication with each other. The 45 notches *f'* are large enough to permit the ball *b* to pass through them but the notches *f* are slightly too small to permit the ball to pass through. The notches are all alike except for this slight difference in size, and 50 this difference in size is preferably so slight as not to be readily discernible by the eye.

To move the ball around from one compartment to another it is simply necessary to tilt the box while holding the same in 55 one's hands, and the problem of the puzzle is to cause the ball to pass from one of the

compartments, namely, the starting compartment through a series of intermediate compartments to a final or goal compartment.

In the drawing I have designated the starting compartment with the word "Start" and the final compartment with the word "Goal." The notches may be so disposed as to enable any two of the compartments to be used respectively as the starting and the goal compartments provided always that the two kinds of notches are so arranged that the ball must take a circuitous passage in order to get from the starting compartment to the goal.

It is important that the blind notches *f* (through which the ball cannot pass) shall closely simulate in appearance the notches *f'* (through which the ball can pass) in order 75 that in shifting the ball from one compartment to an adjacent compartment it will generally require the person attempting to solve the puzzle to test one or more notches with the ball before the real passage is ascertained. The wide variety and the arrangement of the two kinds of notches is obviously 80 within the spirit of the invention but it will be generally desirable to provide the walls of the starting compartment with at least 85 two of the passage-notches *f'* so as to give the solver a choice of directions, and one of these routes may be arranged more circuitous than the other or may be to a blind or cul-de-sac and thus necessitate the retracing of the 90 route at least a part of its length before the ball can be gotten to the goal. This puzzle is especially intended for young 95 children, and for that class it will not only afford a keen amusement but will aid in developing patience and care and the faculties of discernment.

In Fig. 1 is indicated by a dotted line one possible route over which the ball must pass in order to reach the goal. The cells or compartments marked *d'* form a sort of blind or cul-de-sac, and should the ball be passed into these compartments it will be necessary to retrace the route in order to get back on the main route; any number of these blinds 105 or cul-de-sacs may be arranged along the route as is evident.

Having thus described my invention, what I claim as new and desire to secure by Letters Patent, is—

110 A toy puzzle consisting of a base plate having marginal upright flanges and a plu-

rality of intersecting partitions within the box-like receptacle thus formed, these partitions forming a plurality of cells or compartments and said cells being put into communication with each other by means of notches in the lower edges of the partitions, said notches being alike in appearance but differing as to width, and a ball resting on the base plate and adapted to pass through

the larger of the notches, substantially as set forth.

In testimony whereof I hereunto affix my signature in the presence of two witnesses.

CHARLES EDWARD ASHURNER.

Witnesses:

A. T. POWELL,
J. N. HAMNOR.
